MACHINE FOR FORMING PISTONS OF ELLIPTICAL CROSS SECTION

Gilbert D. Stewart, Detroit, Mich., assignor to Ex-Cell-O Corporation, Detroit, Mich., a corporation of Michigan

Application February 3, 1949, Serial No. 74,418

4 Claims. (Cl. 82—20)

The present invention pertains to machines for forming internal combustion engine pistons of special shape and, more specifically, to a novel and improved machine of the general character disclosed in United States Patent No. 2,121,934 issued June 28, 1938, to Ira J. Snader et al.

The pistons of modern internal combustion engines such as those used in aircraft must be designed for operation at high temperature, pressure and speed. Due to the unequal distribution of metal in the piston walls resulting from the formation of wrist pin bosses, such pistons normally tend to expand unevenly. Thus, a piston which is perfectly round when subjected to room temperature will tend to assume a distorted, out-of-round shape when subjected to the substantial operating temperature of the engine within which it may be used. To offset this tendency, engine designers have called for pistons having slightly distorted initial shapes but which, when heated to operating temperature within the engine, will then assume the optimum shape for best performance. Designers have also found that a satisfactory way to achieve this result is to fasten each piston with a cross section approximating that of an ellipse having a minor axis slightly smaller than the normal diameter of the piston and with such axis lying generally parallel to the axis of the wrist pin bosses.

Accordingly, the general aim of the invention is to provide a novel and improved machine for turning pistons of the character set forth so as to impart a predetermined elliptical shape thereto.

Another object is to provide a machine of the foregoing type adapted to fashion pistons of generally elliptical cross section and which will have a predetermined longitudinal taper or flare.

A further object is to provide a machine of the above character which will be susceptible of simple, rapid adjustment and high production operation.

Other objects and advantages will become apparent as the following detailed description proceeds, taken in connection with the accompanying drawings, wherein:

Figure 1 is a fragmentary front elevation of an illustrative machine embodying the invention, such machine being in condition to start an operating cycle.

Fig. 2 is a slightly exaggerated diagrammatical view illustrating the nature of the cut taken on a round work piece by the machine of Fig. 1.

Fig. 3 is a view similar to Fig. 1 but with a portion of the supporting bridge broken away and the machine near the end of its operating cycle.

Fig. 4 is a slightly exaggerated diagrammatical view illustrating the axial flare on a piston produced by the action of the machine shown in Fig. 1.

Fig. 5 is a fragmentary plan view of the machine in the condition illustrated in Fig. 1.

Fig. 6 is an enlarged fragmentary vertical sectional view taken longitudinally through the tool holder and a portion of the spindle assembly.

2

Fig. 7 is a transverse sectional view through the tool holder taken in the plane of the line 7—7 in Fig. 6.

Fig. 8 is an end elevation of the tool holder taken in the plane of the line 8—8 in Fig. 6.

Fig. 9 is a fragmentary vertical sectional view taken through the machine of Fig. 1 and detailing the spindle actuating yoke.

Fig. 10 is an enlarged fragmentary horizontal sectional view taken in the plane of the line 10—10 of Fig. 9.

While the invention is susceptible of various modifications and alternative constructions, a preferred embodiment has been shown in the drawings and will be described below in considerable detail. It should be understood, however, that there is no intention to limit the invention to the specific form disclosed, but on the contrary, the intention is to cover all modifications and alternative constructions falling within the spirit and scope of the invention as expressed in the appended claims.

Referring more specifically to the drawings, the invention is there exemplified in the form of an illustrative turning machine 20 in which it finds particular but by no means exclusive utility. The machine 20 comprises a base 21 having appropriate ways thereon to support and guide a work holding table 22, which in the present instance is longitudinally movable therealong. Rigidly fixed to the table 22 in any suitable manner is a work support 24 having adjacent its upper end an arm 25 extending longitudinally of the machine 20. The arm 25 has incorporated therein suitable detachable clamping means for securing thereto a hollow cylindrical work piece in the form of a rough machined piston P, the details of such clamping means being unimportant for present purposes. Mounted in overlying and straddling relation upon the base 21 is a bridge or saddle 26. The latter, while movable relative to the table 22 and work support 24, may or may not be movable with respect to the base 21. The bridge 26 serves as a support for a tool head 28 and an electric driving motor 29 which transmits power to the tool head via belt 30 and pulleys 31, 32.

The tool head 28 of the machine 20 (Figs. 1 and 3) comprises a stationary body 33 which rotatably supports therein a tubular spindle 34 journaled in spaced apart bearings indicated diagrammatically at 35 and 36, respectively. The pulley 32 is drivingly connected to the left hand end of the spindle 34 (Fig. 10) as by means of a key 37 and a set screw 38. The end of the spindle 34 remote from the pulley 32 is of somewhat larger diameter than the opposite end portion and terminates in an annular face plate 40. The latter has a tapered central socket 41 extending into the diametrically enlarged portion of the spindle 34. The socket 41 is adapted to snugly receive a hollow tapered shank 42 integral with a generally cup-shaped tool holder 43 which is drivingly mounted on the face plate 40. The opening of the tool holder 43 is of suitable size and depth to receive the work piece P as the latter is machined. In the present instance, the tool holder 43 carries a single point cutting tool 44 mounted so as to project in a radial inward direction. The tool 44 may be adjustably secured in various radial positions, within relatively narrow limits, by means of adjusting screw 45 and locking plug 46.

Provision is made for moving the tool 44 in the proper path to define an elliptical cross section in the work piece P. This is accomplished preferably by mounting the tool head 28 with the longitudinal axis of its spindle lying in a vertical plane passing through the longitudinal axis of the work supporting arm 25 and work piece P, but skewed at a slight angle with regard to the latter axis. With the tool head thus mounted, the cutting tool

44 is caused to move in an orbital path, the plane of which is inclined at a slight angle to the axis of the arm 25 and the work piece P. This orbital path, although circular, will generate an ellipse E when projected upon the cross section of the work piece P, as indicated diagrammatically in Fig. 2. To project the path of the tool 44 upon the cross section of the work piece, provision is made in the machine 20 for moving the work support 24 relative to the tool head 28. A convenient way to accomplish this is to slide the work holding table 22 along the ways of the base 21 and toward the bridge 26.

To secure the tool head 28 in the manner described above, the bridge 26 has associated therewith a wedge block 47 (Fig. 3) having a flat upper surface 48 sloping downwardly in the direction of the work holding table 22. Mounted at spaced apart points along the surface 48 are a pair of cleats or abutments 49 secured in place as by cap screws 50. The underside of the body 33 is fashioned with a plane surface 51 which abuts the surface 48, the surface 51 being interrupted by a pair of transverse grooves 52 which house the cleats 49. To permit limited adjustment of the tool head 28 upon the wedge block 47, the grooves 52 are made substantially wider than the cleats 49. Set screws 53 carried by the body 33 and adjustable from the exterior thereof serve to clamp it to the cleats 49.

Means is provided for automatically regulating the size of the cross section generated in the work piece P as the latter advances axially relative to the cutting tool 44. This is accomplished in the machine 20 by the use of means for progressively changing the radial position of the cutting tool 44 during its period of engagement with the work piece P. Referring more specifically to Figs. 3, 6, 7 and 8, it will be perceived that a tool carrying arm 54 is pivotally secured to the tool holder 43 as by means of a pin 55 located close to the tool 44. The arm 54 runs generally parallel to the axis of the tool holder 43, terminating in a bifurcated end portion comprising spaced apart knuckles 56. A biasing spring 58 tends to urge the bifurcated end of the arm 54 toward an extreme radial outward position which corresponds to the extreme radial inward position of the cutting tool 44. The radial position of the arm 54 and the tool 44 is governed by means of a slide 59 housed within a transverse bore 60 in the tool head and adapted to reciprocate within narrow limits along the bore 60. Adjacent one end thereof, the slide 59 is formed with a pair of diametrically opposed notches 61 which receive the knuckles 56 of the tool carrying arm 54. To counterbalance the weight of the arm 54, a portion of the tool holder wall diametrically opposite the arm 54 is thickened as at 62.

For the purpose of coordinating the radial position of the tool 44 and the arm 54 with the relative bodily movement between the work support and the tool holder 43, a simple yet highly effective arrangement is utilized. Briefly, such arrangement comprises displaceable means carried by the bridge 26 and adapted, when actuated by the approaching work support 24, to rock the tool carrying arm 54 and the tool 44 into the desired radial position. In the present instance, the bridge 26 carries a linkage comprising a control bar 63, a rockable yoke 61, and an actuating shaft 65 rotatable with the spindle 34 but axially slidable within the same. The bar 63 is disposed longitudinally of the machine 20, being slidably supported within a bore in the wedge block 47 by means of a pair of spaced apart guide bushings 66. The latter serve to maintain the bar 63 in alignment with a bumper 67 on the work support 24, the bumper being adapted to accost the free end of the bar 63 during the machining of the work piece P.

The rockable yoke 64 (Figs. 1, 3, 9 and 10) which translates the axial movement of the control bar 63 into axial movement of the actuating shaft 65, is provided with a pair of bushings 68 which engage a corresponding pair

of fixed supporting trunnions 69, the latter being mounted on the bridge or saddle 26 as by means of suitable brackets. The depending end of the yoke 64 terminates in a pair of spaced apart bosses 70, each having an inwardly projecting pivot pin 71 threadedly secured thereto. The pins 71 engage an enlarged abutment member 72 rigidly fixed to the control bar 63. The member 72 is provided with a pair of vertical slots 73 of suitable size to receive the inner ends of the pins 71 and to permit movement of the latter along the slots 73. The upstanding end of the yoke 64 also terminates in a pair of spaced apart bosses 74, each of the latter carrying an inwardly projecting pivot pin 75 having a slide block 76 journalled thereon. The blocks 76 are arranged for coaction with a relatively large and substantially rectangular abutment member 78 mounted on the shaft 65 adjacent the spindle driving pulley 32. The member 78 is formed with a relatively wide vertical groove 79 on either side thereof to slidably receive the blocks 76.

In order to eliminate excessive wear which might otherwise occur in the parts connecting the yoke 64 and the rotating actuating shaft 65, the abutment member 78 is journalled on the shaft 65 as by means of a pair of axially spaced bearings 80. The latter are mounted on a portion of the shaft 65 of reduced diameter and are locked against axial movement relative thereto by means of a washer 81, sleeve 82, washer 84, and retainer boss 85. The bearings 80 are protected against the entry of chips and other foreign material by means of end caps 86 rigidly attached to the member 78.

For the purpose of effecting reciprocatory movement of the slide 59 in response to axial movement of the actuating shaft 65, the end of the latter adjacent the tool holder 43 has a cam portion 88 integral therewith (Figs. 6 and 8). The cam portion 88 is slotted longitudinally over a substantial portion of its length so as to define a pair of laterally spaced cam fingers 89 which straddle central portion 90 of the slide. Each of the fingers 89 is formed with a relatively flat guide surface 91 running substantially parallel to the axis of the shaft 65 and a cam surface 92 having a moderate curvature along its length. Freely journalled on central portion 90 of the slide 59 and adapted to shift the latter through coaction with each of the cam surfaces 92 is a pair of follower rollers 94. Freely journalled on pin 95 fixed to the tool head 43 and adapted to bear against the guide surfaces 91 is a pair of reaction rollers 96. The latter are disposed in straddling relation with the central portion 90 of the slide, such portion being formed with an oblong slot 98 to effect clearance with the pin 95 which does not move with the slide.

With the arrangement thus far described, the bumper 67 of the work support would engage the control bar 63 only when moving to the left as viewed in Figs. 1 and 3. Thus, in order to position the bar 63 accurately when the work support 24 is moving in the opposite direction, some sort of loading or biasing device must be utilized. In the present instance, such device happens to be a fluid actuator 99 mounted on the bridge 26 and connected with the end of the control bar 63 adjacent the yoke 64. With this construction, when the work support 24 moves to the right (as viewed in Figs. 1 and 3), the actuator 99 causes the end of the control bar 63 to remain in engagement with the bumper 67. Such action continues until adjustable stop 100 on the bar 63 accosts guide bushing 66 of the wedge block 47.

To protect the machine 20 against abnormal movement of certain parts and also to facilitate the setting up of an automatic operating cycle, a plurality of limit switches and stops may be employed. Thus there is fixed to the work holding table 22 a dog bar 102 (Fig. 1) which carries a stop dog 104 and various other control dogs (not shown). Rigidly secured to the base 21 in position to be actuated by the dog 104 when the table 22 reaches its extreme right hand position (as viewed in Fig. 1) is a limit switch

plunger 105. The latter, when actuated, serves to arrest the table 22 against further rightward movement.

For the purpose of actuating an appropriate control when the tool 44 has reached either extreme of its radial movement, there is operatively associated with the yoke 64 a pair of limit switches 106, 108. The switch 106 is arranged for actuation when the tool 44 has reached its extreme radial inward position. Under such circumstances, the machine is in the condition indicated in Fig. 1 and the yoke 64 is inclined away from the work piece. To enable the yoke to trip the switch 106, the former is provided with a leg 109 having an adjustable tip 110 adapted to engage a roller 111 carried by a tripping arm 112 on the switch 106. When the tool 44 reaches its extreme radial outward position, as indicated in Fig. 3, the yoke 64 inclines toward the work piece and an extension 114 on the former accosts roller 115 and tripping arm 116 on the limit switch 108.

While the operation of the machine 20 will doubtless be readily apparent to those skilled in the art, a brief résumé thereof might be appropriate at this point. Assume first that the machine is in the condition of Fig. 1 with a work piece P secured skirt-first to the arm 25 and the cutting tool 44 at its extreme radial inward position. Upon initiation of the operating cycle, the tool head 28 is brought up to speed and the work holding table 22 slides toward the bridge 26. This brings the head end portion of the work piece into contact with the tool 44 without causing engagement of the control bar 63 by the bumper 67. With further movement of the table 22 toward the bridge 26, the entire ring belt of the work piece P is given an elliptical cross section which is substantially constant axially of the work piece P. As the tool 44 commences to machine the skirt portion of the work piece adjacent the ring belt, the bumper 67 accosts the end of the control bar 63 and causes the latter to move leftward (as viewed in Figs. 1 and 3) toward its retracted position. Such action produces a proportional movement of the yoke 64, the actuating shaft 65, the cam arms 89, the slide 59, the tool carrying arm 54, and finally, the cutting tool 44. With continued movement of the table 22 toward the bridge 26, the tool 44 is caused to move progressively outward and travels in an orbit of ever increasing diameter. This causes the tool 44 to define in the work piece P a substantially elliptical cross section of gradually increasing area toward the skirted end of the work piece, thus producing the flared skirt indicated in Fig. 4. After the work piece P has been completely machined, it is permitted to overrun the tool 44 by a slight amount. By reason of the increasing steepness of the cam surfaces 92 as the extreme radial outward position of the tool 44 is approached, such action is sufficient to move the tool clear of the periphery of the work piece and thus avoid an undesirable tool dragout line when the work piece is withdrawn from the tool holder.

I claim as my invention:

1. In a machine for forming pistons of elliptical cross section gradually increasing in area axially thereof, the combination comprising a base, a work support adapted to clamp a work piece with its axis extending along said base, a tool head, means for mounting said work support and said tool head for relative bodily movement along said base, a spindle journaled in said tool head for rotation about an axis intersecting the axis of the work piece and fixed with respect thereto but skewed with respect to the direction of said relative bodily movement, a tool holder rotatable with said spindle, a cutting tool carried by said tool holder and mounted for radial shifting movement therein, cam and follower means for shifting said cutting tool radially without changing the angle between the axes of said spindle and the work piece, and a motion transmitting linkage interposed between said work support and said cutting tool, said linkage being disposed in position to actuate said cam and follower

means and thereby effect a progressive change in the radial position of said cutting tool as an incident to said relative bodily movement between said work support and said tool head.

5 2. In a machine for forming axially flared pistons of elliptical cross section from generally cylindrical work pieces, the combination comprising a base, a bridge disposed in overlying and straddling relation with said base, a work holding table mounted on said base for longitudinal sliding movement relative to said bridge, a work support on said table adapted to hold a work piece with its axis extending in the direction of said relative longitudinal sliding movement, a supporting block on said bridge, a tool head fixed to said supporting block and having an axis 10 adapted to intersect the axis of the work piece at a relatively small acute angle, a hollow spindle journaled in said tool head and terminating in a face plate, a generally cup-shaped tool holder mounted in abutment with said face plate and bodily rotatable therewith, a tool carrying 15 arm rockably mounted in said tool holder, a slide in said tool holder adapted to rock said tool carrying arm into various radial positions, a control bar slidably mounted in said supporting block and disposed for abutting engagement with said work support, an actuating shaft housed 20 within said hollow spindle, cam means fixed to said actuating shaft for positioning said slide in response to axial movement of said shaft, and a rockable yoke pivotally mounted on said bridge and adapted to transmit axial motion from said control bar to said actuating shaft.

25 3. In a machine for forming axially flared pistons of elliptical cross section from generally cylindrical work pieces, the combination comprising a base, a hollow spindle and a work holding table mounted on said base for longitudinal sliding movement relative to each other, said 30 spindle being rotatable about an axis skewed with regard to said longitudinal sliding movement, a work support fixed to said table adapted to clamp a work piece with its axis extending in the direction of said relative longitudinal sliding movement and intersecting the axis of said 35 spindle, a bumper on said work support, a tool holder mounted for bodily rotation with said spindle, a tool carrying arm pivotally secured to said tool holder for radial movement relative thereto, a slide in said tool holder adapted to rock said tool carrying arm into various radial 40 positions, a reciprocable control bar disposed for engagement with said bumper on said work support, loading means for urging said control bar toward said bumper, an actuating shaft housed within said hollow spindle and rotatable therewith but axially movable therein, cam 45 means fixed to said actuating shaft for positioning said slide in response to axial movement of said shaft, and a rockable yoke adapted to transmit axial motion from said control bar to said actuating shaft.

4. In a machine for forming pistons of variable cross section, the combination comprising a base, a work support mounted for longitudinal movement on the base, a supporting block associated with the base, a tool head on the supporting block, a cup-shaped tool holder mounted in the tool head, said holder having a thickened wall portion running axially thereof, a tool carrying arm rockably mounted in said tool holder and located diametrically opposite said thickened wall portion, a cutting tool fixed to said arm, a reciprocable slide mounted in said tool holder and adapted to rock said arm radially, follower 60 means on said slide, cam means adapted to coact with said follower means to effect radial adjustment of said cam and said cutting tool, a control bar mounted in the supporting block and disposed for abutting engagement with the work support and connecting linkage between the control bar and the reciprocable slide and the tool holder, whereby relative movement between the work support and the supporting block will effect a radial adjustment of the cutting tool.
